UNITED STATES PATENT OFFICE.

JAMES H. NORTHROP, OF HOPEDALE, MASSACHUSETTS, ASSIGNOR TO THE DRAPER COMPANY, OF SAME PLACE AND PORTLAND, MAINE.

THREAD-CUTTING TEMPLE FOR LOOMS.

SPECIFICATION forming part of Letters Patent No. 604,632, dated May 24, 1898.

Application filed December 6, 1897. Serial No. 660,866. (No model.)

To all whom it may concern:

Be it known that I, JAMES H. NORTHROP, of Hopedale, county of Worcester, and State of Massachusetts, have invented an Improvement in Thread-Cutting Temples for Looms, of which the following description, in connection with the accompanying drawings, is a specification, like letters on the drawings representing like parts.

10 This invention relates to that class of loom-temples more particularly adapted for so-called "automatic" looms, wherein the filling is supplied to the shuttle in the shuttle-box while the loom is running, a fresh filling-carrier being inserted into the shuttle while the more or less exhausted filling-carrier is ejected therefrom upon breakage or failure of the filling. Each insertion of a fresh filling-carrier leaves outside of the selvage a filling end, 15 and a thread-cutting temple has been devised to sever this filling end before the temple is moved toward the breast-beam as the lay beats in the filling, as in United States Patent No. 585,465, dated June 29, 1897. It 20 is customary to attach a strip of leather to the lay to cushion or break the force of the blow upon the temple, and in order to permit the proper adjustment of the temple for different widths of goods the leather strip must 25 be of considerable length. In my present invention I mount the cushion on the temple, thereby greatly reducing the amount of cushioning material required and lessening the expense, and, furthermore, the operation of 30 the device is improved.

35 Figure 1 is a top or plan view of a thread-cutting temple with my invention applied thereto. Fig. 2 is a side elevation thereof, and Fig. 3 is a front end elevation thereof.

40 The stand A, adapted to be secured to the breast-beam of the loom, the slide-bar B, having the pod B', the cap B², the heel B³, attached to the pod, and the toothed roller B⁵ are and may be all as usual.

45 The blade a' in the slotted pod, the slotted ear b on the bar B to receive the body c of the thread-cutter C, (shown as slotted to leave

two hooked arms c c² and straddling the blade a,) and the spring d, one end of which engages the heel c⁴ of the cutter to retain the cutter in its normal forward position, with its cutting end out of the plane of the filling end, may be and are substantially as shown in the United States Patent No. 585,465, to which reference may be had.

50 As shown in Fig. 3, the heel B³ is at one side of the heel c⁴ of the cutter, and the latter is in advance of the former, to be engaged first by the lay as it beats up to thereby first rock the cutter, placing the hooked end 55 thereof behind the filling end, the further forward movement of the lay causing the cutter to be drawn into the temple-head, as in the patent referred to, drawing the filling end across the blade a' and severing the end at 60 that point usually before the heel B³ of the temple is engaged by the lay to move the temple and the cutter back for their full stroke.

65 Upon the heel B³ of the temple I attach a cushion, shown as a piece of leather M, held in place by a rivet m, or in other suitable manner, the cushion passing across the front of the heel and extending laterally in front of the heel c⁴ of the cutter, but unattached 70 thereto. This cushion is thus interposed between the two heels and the lay and breaks or relieves the force of the blow. Whatever 75 the adjustment of the temple the cushion is always in proper position. It is in plain 80 sight of the weaver and can be readily renewed when worn. It is small in extent and readily secured in place.

Having fully described my invention, what I claim, and desire to secure by Letters Patent, is—

85 1. A reciprocating temple provided with a depending heel and a blade, a coöperating cutter-blade having a heel, said heels being adapted to be engaged and moved by the lay, 90 and a cushion attached to the temple-heel and extended laterally in front of but unattached to the heel on the cutter-blade.

2. A reciprocating temple provided with a

blade, a coöperating cutter-blade having a heel adapted to be engaged by the lay, and a flexible cushion attached to the temple and extended in front of and independent of the heel of the cutter-blade, to break the force of the blow of the lay thereupon.

In testimony whereof I have signed my

name to this specification in the presence of two subscribing witnesses.

JAMES H. NORTHRUP.
